UNITED STATES PATENT OFFICE.

WILLIAM ERNST AND ALVA A. PATTON, OF SAN FRANCISCO, CALIFORNIA.

TUBE-CLEANER.

1,097,309.

Specification of Letters Patent.

Patented May 19, 1914.

Application filed May 4, 1908. Serial No. 430,728.

To all whom it may concern:

Be it known that we, WILLIAM ERNST and ALVA A. PATTON, citizens of the United States, residing at San Francisco, in the 5 county of San Francisco and State of California, have invented certain new and useful Improvements in Tube-Cleaners, of which the following is a specification.

Our invention relates to improvements in 10 tube cleaners.

The object of said invention is to provide a tube cleaner that is uniform and rapid in 15 operation, simple in construction, easily adjusted and which operates with a minimum of power, the same being particularly applicable to boiler tubes.

Our invention consists in the novel arrangement and combination of parts described in the following specification, shown 20 in the accompanying drawing and claimed in the appended claim.

Referring to the accompanying drawing, Figure 1 is a side view of our tube cleaner. Fig. 2 is a longitudinal section of the same 25 and Fig. 3 is an end of the same, looking from the left of Fig. 1.

In the figures, A shows the frame of said tube cleaner. Said frame has the arms 2 carrying a shaft to which is securely fastened the cutters 4 and 5 having teeth 6 and 30 7 respectively. 8 is the spacing sleeve and 9 is a nut for clamping the cutters 4 and 5 on the shaft 3. In the outer end of each of the arms 2 is inserted a pin 10 adapted to 35 retain the shaft 3 within the slots 2 formed in said arms.

11 is a hub on frame A to which is fastened the shaft 12 driven by any suitable 40 source of power. The shaft 3 is mounted eccentric to driven shaft 12 and is impelled centrifugally in the said slot 2' toward the surface of the tube with which teeth 6 and 7 contact in the revolution of said shaft 12.

The motion imparted to the device in its 45 operation is that of a crank shaft, as that of a straight shaft would result in the cutters remaining in the same position, the bases of the slots as shown in Fig. 2 being above the center of shaft 12 so as to impart such a 50 differential motion as to produce a combined

grinding and beating effect by the movement of the shaft 3, giving the maximum result.

The ends of the cutter 4 and the inner end of the cutter 5 are preferably curved 55 convexly so as to avoid contact with adjacent parts when the same are worn except at the center of the same, thereby reducing friction. The outer end of the cutter 5 is preferably straight so as to give a greater 60 cutting surface at such point. The preferred form of the teeth of the cutters as shown in Fig. 3, is such as to give the best results in the removal of the incrustations in tubes or other parts wherein the device is 65 intended to be used by reason of their width—thus giving increased strength and power in the work. If desired the shaft 3 may be shortened, and the same threaded in proximity to sleeve 8 and the nut 9 secured 70 thereon so that merely the cutter 4 will be in use. Our device may be used under varying speeds of rotation of the shaft 12 whereby the device is operated.

3' shows a boss which is secured to shaft 75 3 and countersunk into cutter 4. Said boss presents an even surface to the contiguous arm 2, the same acting as a guide as well as a support for said arm. The convex curving of the cutters, as mentioned, gives a longitudinal pushing movement to the incrustations encountered.

The device having but a single frame A and the arms thereof being parallel, and one of said arms being secured centrally by a 85 shaft as shown in Fig. 1 and Fig. 2, a roller or cutter of far greater weight and diameter may be used than if the device employed a central shaft with the rollers or cutters positioned and operating on the sides thereof, 90 thereby giving the device increased power and efficiency, besides requiring less power to operate one or more of the rollers or cutters as illustrated, the same being but slightly eccentric and the rotation attainable 95 being very high.

We claim:—

A tube cleaner consisting of an operating shaft, a head or frame detachably secured thereto, said head having parallel arms with 100

open slotted ends and a connecting wall for said arms; a rotatable shaft having a boss thereon and seated in said slotted arms, a cutter on said shaft and means closing said 5 open slotted ends, said cutter shaft being on one side of the center of said operating shaft and said cutter extending on the opposite side thereof.

In testimony whereof we affix our signatures, in presence of two witnesses.

WILLIAM ERNST.
ALVA A. PATTON.
